UNITED STATES PATENT OFFICE.

JOSEPH NICHOLS, OF CHICAGO, ILLINOIS.

HINGE.

SPECIFICATION forming part of Letters Patent No. 517,124, dated March 27, 1894.

Application filed May 31, 1893. Serial No. 476,069. (No model.)

To all whom it may concern:

Be it known that I, JOSEPH NICHOLS, a citizen of the United States, residing at Chicago, in the county of Cook and State of Illinois, have invented a new and useful Improvement in Hinges, of which the following is a specification.

My invention relates especially to the class of hinges used for triple mirrors, used by gentlemen's furnishing houses, and is especially designed for use where it is desired to swing the hinged article through as large an angle as possible, and clear the post or fixture to which the hinge is fastened.

Reference will be had to the accompanying drawings in which—

Figure 1 is a side vertical view of a mirror hinged to a post. Fig. 2 is a front view of one hinge and post, the mirror removed, showing the shank of the hinge in section. Fig. 3 is a top plan view of the hinge with the shank of the hinge in dotted lines, and the pivot points of the shank in section. Fig. 4 is a side sectional view on the line 4. 4. Fig. 2. Fig. 5 is a bottom plan view of the hinge. Fig. 6 is a side sectional view on the line 6. 6. Fig. 3.

In the drawings —A— designates a mirror to which there is attached the shanks "C" of the hinge, the body of the hinge "D" being fastened to post "B." To the shank "C" of the hinge, there are fixed pivot pins "C²," "C⁵," "C⁸." "C⁵" is shorter than "C²" and "C⁸" for the purpose of clearing the fins "D," as will be described later, and "C²," and "C⁸" are provided with slots "C⁴" to engage fins "D."

In the main body of the hinge "D" there is a guideway "d," which engages the pivot pin "C⁵" during a part of the revolution of the hinge, which guideway is shaped to conform to the movement of the shank when guided by the pins "C²" and "C⁸," when in engagement with fins "D," and also to guide the shank in conjunction with either pin "C²" or "C⁸" alone, when the same is over and revolving on the center of studs "D²" or "D⁸," until the position of the flange "d²" or "d⁸" is such as to hold the pin "C²" or "C⁸" in position without the aid of pin "C⁵."

In the body of the hinge "D" there is pivoted at the points "d⁹" (Fig. 6) two studs

"D²," "D⁸" which are provided with end flanges, "d²," "d⁸" to correspond with the fins "D," and at the lower end of these studs 55 there are flanges, "D⁴" which have notches "e⁸" shown in the dotted lines, Fig. 3., and these studs are held up in position by the brackets "d⁸." To the body "D" of the hinge, underneath the flange "d¹⁰," there is fixed at 60 "e," a spring "E" which spring E has projections "e¹," "e²" shown in dotted lines in Figs. 2 and 3, which projections "e¹," "e²" engage the notches "e⁸" in the flange "D⁴" of the studs "D²," "D⁸." Two of the notches e⁸ 65 are shown, one is to hold the stud in position so that the flanges "d²," "d⁸" will be in line with the fins "D," and the other one is to steady the mirror in a position at which it is frequently used, and thus a number of such 70 notches may be made in the flange "D⁴" to suit the cases required. The fins "D" are cut away at "d⁸" to permit the pins C⁸, C² to pass out at the period of the revolution when one of them centers on the studs "D²," "D⁸." 75

The operation of the hinge from the central position shown in the drawings is thus, in moving in either direction the pins "C²," "C⁸" with their slots "C⁴" ride on the fins "D," and the pin "C⁵" moves in slot "d," which 80 conforms to the movement produced by the fins "D," and when one pin say "C²" centers over flange "d⁸" of stud "D⁸" as it ceases to move farther in the line of fin "D," but turns on the center of stud "D⁸" which movement turns the stud also as slot "C⁴," engages flange "d⁸" and the shank "C" revolving on the pivot "D⁸" revolves pin "C⁸" out of engagement with fins "D" through the space "d," and the pin C⁵ clears slot "d" and passes 90 out over fin "D," and the revolution of the stud "D⁸" prevents the disengagement of the pin "C²," and the flange "d⁸" of the body "D" sustains the outward strain of the pin "C²." This is shown by the dotted position "C" Fig. 3. wherein "d" indicates the position of flange "d⁸." Thus this hinge makes possible almost a complete revolution and at the same time clears a space wherein a post may stand to sustain the hinged article. 95

What I claim is—

1. In a hinge the combination of the body "D" formed with the guideway "d," the revoluble studs "D²" and "D⁸" seated therein

near the inner edge and on opposite sides thereof, and the curved fins "D'" on its outer edges, of the shank "C" having pin "C⁵" to engage said guideway, and slotted pins "C²" 5 and "C³" on the inner end and opposite sides of said shank to engage said fins, whereby the guideway "d," pins "C⁵," fins "D'," pins "C²" and "C³" sustain and carry the shank through the central portion of the revolution, while 10 studs "D²" and "D³" carry the said shank during the balance of the revolution, substantially as, and for the purpose shown and described.

2. In a hinge the combination with the body 15 "D" provided with two revolute stud pivots "D²," "D³" at the sides thereof, and having flanges "d²," "d³," of shank "C" having pins adapted to engage said studs, during a part of the revolution of the hinge, of an independent carrying device for carrying the shank of 20 the hinge through the period of revolution, clearing the space occupied by the sustaining post for the purpose shown.

3. A hinge having a shank "C," having 25 pins "C²" and "C³" at the inner end and opposite sides thereof, a body "D" having revolute studs "D²" and "D³" at the opposite sides thereof, said pins "C²" and "C³" engaging the studs "D²" and "D³" through 30 parts of the revolution of the hinge, substantially as shown and described, combined with a spring engaging locking device to hold the

studs "D²" and "D³" in position for the purpose described.

4. A hinge having a shank "C" having 35 pins "C²" and "C³" at the inner end and opposite sides thereof; a body "D" having revolute studs "D²" and "D³" at the opposite sides thereof; said pins "C²" and "C³" engaging the studs "D²" and "D³" through 40 parts of the revolution of the hinge substantially as shown and described, combined with a spring engaging locking device to hold studs "D²" and "D³" in position for the purpose described; said locking device consisting of a flange "D⁴" on said studs having notches "e," a spring catch "E" engaging 45 said notches as shown.

5. A hinge having a shank "C," having pins "C²" and "C³" at the inner end and opposite sides thereof; a body "D" having revolute studs, pivots "D²" and "D³" at the opposite sides thereof, and flanges "d⁴" outside of said studs combined and arranged substantially as shown, and for the purpose 50 described.

In witness whereof I have hereunto subscribed my name in the presence of two witnesses.

JOSEPH NICHOLS.
